UNITED STATES PATENT OFFICE.

FRANK M. THOMAS, OF CATSKILL, NEW YORK.

DESIGN FOR A FLAG, SIGN, BADGE, OR EMBLEM.

51,126.

Specification for Design.

Patented Aug. 7, 1917.

Application filed May 22, 1916. Serial No. 99,241. Term of patent 3½ years.

To all whom it may concern:

Be it known that I, FRANK M. THOMAS, a citizen of the United States, residing at Catskill, in the county of Greene and State of New York, have invented a new, original, and ornamental Design for a Flag, Sign, Badge, or Emblem, of which the following is a specification, reference being had to the accompanying drawing, forming part thereof.

The figure is a plan view of an emblem, showing my new design.

I claim:—

The ornamental design for a flag, sign, badge, or emblem, as shown.

FRANK M. THOMAS.
